UNITED STATES PATENT OFFICE.

CHARLES BARRIE POOL AND ROBERT WINFORD POOL, OF STAMPS, ARKANSAS.

SHIPPING CONTAINER.

Application filed February 27, 1925. Serial No. 12,060.

Our invention relates to shipping containers, and it consists in the combinations, constructions and arrangements herein described and claimed.

5 An object of the invention is to provide a container which is constructed in such manner that pilfering of the contents thereof without permanent injury to the crate is prevented.

10 A further object of the invention is the provision of a shipping container having a body and top and bottom members formed separate from one another, the top and the body and the bottom and the body having 15 co-engaging locking members for holding the top and the bottom against displacement from the body after they have been applied to the body until the fastening means or the container proper have been broken.

20 A further object of the invention is the provision of a container having top and bottom members formed separate from the body of the container and adapted to be applied to the body and secured against displacement without there being any necessity of 25 securing any nails or like fastening devices in the body at the time of the application of the top and bottom thereto.

A still further object of the invention is 30 the provision of a container of the character described which is extremely strong and durable yet light in weight for a container of a given capacity, and which is thoroughly practical commercially.

35 Other objects and advantages of the invention will be apparent from the following description, considered in conjunction with the accompanying drawings forming a part of this application, in which—

40 Figure 1 is a perspective view of the improved container, and

Figure 2 is a longitudinal vertical section through the container.

The embodiment of the invention illustrated in the drawings is a crate although it will be understood from the following description that the invention may be embodied in a box or other case having imperforate walls.

45 The crate shown in the drawings has a body which is substantially rectangular in cross sectional contour. This is the preferred but not necessarily the only form of crate body which the invention may embody.

50 The crate body comprises four corner posts 1. Adjacent spaced horizontal side bars or

slats 2 are connected by nails 3 or like fastening devices to the side faces of adjacent corner posts. Upper and lower horizontal end bars or slats 4 and 5 respectively are 60 secured by nails 6 to adjacent corner posts, each bar 4 having the end portions thereof secured upon the upper ends of a pair of adjacent corner posts 1 and each bar 5 likewise having the end portions thereof secured 65 upon the bottom ends of a pair of adjacent corner posts 1. Spaced vertical side slats 7 are secured by nails 8 or like fastening devices to the horizontal side bars 2 against the inner faces of side bars 2 so that the 70 respective vertical slats 7 extend above the upper edge of the upper horizontal bar 2 and below the lower edge of the lower bar 2. The upper ends of the respective slats 7 are flush with one another as are the lower 75 ends of the respective slats 7.

The crate body also includes spaced vertical end slats 9 secured to the horizontal end bars 4—5 against the inner faces of said horizontal end bars by nails 10 or like 80 fastening devices. The vertical end slats 9 extend above the upper edges of the upper bars 4 and terminate at their upper ends slightly above the level of the upper ends of the vertical slats 7. The vertical 85 end slats 9 also extend below the lower edges of the lower bars 5 and terminate at their lower ends slightly below the level of the lower ends of the vertical slats 7.

The bottom unit of the crate comprises a 90 rectangular frame consisting of a pair of bottom end bars 11 connected together at their ends and held in spaced parallel relation by parallel bottom side bars 12, the connection between meeting ends of bars 11 95 and 12 being effected by nails 13 or like fastening devices. The bottom unit also includes spaced longitudinal bars 14 arranged between the bottom end bars and secured to the latter by nails 15 or like fastening devices. Bottom transverse bars or slats 16 extend across the inner faces of the longitudinal bars 14 and are secured to the latter by nails 17 or like fastening devices. The bottom frame is adapted to fit 100 over the depending end portions of the vertical slats 7 and 9 until the upper edges of the bottom end members 11 abut the lower horizontal end bars 5, and the lower 105 ends of the vertical slats 7 abut the transverse bottom slats 16. A horizontal locking bar or lug 18 is secured against the

110

outer faces of the lower end portions of the vertical slats 9 at each end of the body of the crate by means of nails 19 or like fastening devices in position to enter and engage with a recess 20 in the inner face of the adjacent bottom end member 11 when the bottom is applied to the body of the crate. The upper wall of the recess 20 is horizontal, as at 21, while the lower wall 10 of the recess 20 is inclined, as at 22. The locking bar 18 has the upper and lower faces thereof formed to closely engage with the upper and lower walls of the recess 20 in which the locking bar is received when the 15 bottom unit is applied to the body of the crate. The bottom unit therefore can be quickly and easily applied to the body of the crate by placing one end of the bottom in place with one of the end locking 20 bars 18 in place in the corresponding recess 20 and then pressing on the other end of the bottom and inwardly on the slats 9 at the other end of the body of the crate until the second locking bar 18 snaps into place 25 in the second recess 20. The bottom then will be secured against displacement from the body and cannot be removed from the body except by the use of tools and sufficient force to break members of the bottom or the 30 body.

The top or cover unit of the crate is similar to the bottom unit except in one particular which will be pointed out. The top unit comprises a rectangular frame adapted 35 to fit over the extending upper end portions of the slats 7 and 9. This top frame comprises end bars 23 and 24, respectively, side bars 25 spaced longitudinal top bars 26, and spaced transverse top bars 27 which extend across the under faces of the bars 26. Meeting or superposed portions of the members of the top unit are secured to each other 40 by nails 28 or like fastening devices.

The end top member 23 is similar to each 45 of the end bottom members 18 and has a horizontal recess 29 in its inner face adapted to receive and engage with a horizontal locking bar 30 which is securely fastened by nails 31 or like fastening devices onto the outer faces of the upper end portions 50 of the vertical bars 9 at one end of the body of the crate. The lower wall of the recess 29 is horizontal while the upper wall of the recess 29 is inclined and the upper 55 and lower walls of the locking bar 30 are correspondingly formed.

A metal fastening strap 32 which is strong but at the same time bendable is attached 60 at one end upon the middle longitudinal bar 26 of the top and is formed with an opening 33 adjacent to its other end adapted to engage with a headed fastening member 34 which protrudes from the inner face 65 of the adjacent upper horizontal end bar 4. The strap 32 is of sufficient length to

hold the end bar 24 of the top unit firmly on the corresponding horizontal end bar 4 when the strap has been engaged with the fastening member 34 and the top unit then has been pressed down over the extending 70 upper end portions of the vertical slats 7 and 9 until the horizontal locking bar 30 has snapped into place in the recess 29. The top then cannot be removed intact from the body of the crate until the fastening strap 75 32 has been cut or otherwise broken.

From the foregoing description of the various parts of the device, the operation thereof may be readily understood. The top and bottom will reenforce the body of 80 the crate or other form of container embodying the invention and will prevent outward bulging of the walls of the body because of pressure from the inside of the body. The improved container therefore 85 will be extremely strong and durable while it also may be light in weight. Moreover, the pressure on the body from the inside because of the filling of the body of the container tends to make more secure the already stable and positive engagement of the locking bars on the body with the recesses 90 in the top and bottom members. The top cannot be displaced from the body and the top and body left intact until the fastening 95 strap 32 has been broken nor can the bottom be displaced from the body without serious injury to the bottom or body. Therefore pilfering of the contents of the container 100 while it is in transit without noticeable and serious injury to the container is practically prevented.

Obviously, the invention is susceptible of embodiment in forms other than that which is illustrated in the accompanying drawings 105 and we therefore consider as our own all such modifications and adaptations thereof as fairly fall within the scope of the appended claims.

We claim:—

1. In a container of the character described, a vertical body open at one end, a cover for said end, said cover including a frame fitting over said end portion of the body, said cover frame having horizontal recesses in inner faces of opposite members thereof, and locking bars on opposite members of the body adapted to enter and engage with said recesses to hold said cover permanently in place, the inner walls of said recesses being horizontal, the outer walls of said recesses being inclined, and the inner and outer walls of said locking bars being fashioned to closely contact with the corresponding walls of the recesses, said locking bars being completely covered by said frame members when said locking bars are engaged with said recesses.

2. A crate comprising a body rectangular in cross sectional contour, said body com-

prising corner posts, longitudinal side bars secured to the side faces of adjacent corner posts, vertical side bars secured to the inner faces of the horizontal side bars and extending above and below the levels of the corner posts, horizontal end bars respectively secured on the upper and lower ends of adjacent corner posts, vertical end bars secured to the inner faces of the horizontal end bars and extending above and below the corner posts, a bottom comprising a rectangular frame and transverse and longitudinal bottom head members, said frame being adapted to fit over the extending lower end portions of said vertical body bars until certain of said vertical bars abut certain of said head bars and the end members of the frame rest upon the horizontal end body members, said end members of the bottom frame having horizontal recesses in their inner faces, horizontal locking bars on said lower end portions of the vertical end bars adapted to enter and engage with said recesses, a top having a rectangular frame adapted to fit over the extending upper end portions of the vertical bars of the body and having head members adapted to abut the upper ends of said vertical body bars, and means for securing the top in place.

30 3. A crate comprising a body rectangular in cross sectional contour, said body comprising corner posts, longitudinal side bars

secured to the side faces of adjacent corner posts, vertical side bars secured to the inner faces of the horizontal side bars and extending above the levels of the corner posts, horizontal end bars respectively secured on the upper and lower ends of adjacent corner posts, vertical end bars secured to the inner faces of the horizontal end bars and extending above the corner posts, a bottom permanently secured to the lower end of said body, a top having a rectangular frame adapted to fit over the extending upper end portions of the vertical bars of the body, one end member of the top frame having a horizontal recess in its inner face, a horizontal locking bar on the extending upper end portions of the corresponding vertical bars adapted to enter and engage with said recess, a headed pin extending inwardly from the second end member of the top frame, and a strap having an end portion permanently secured to the head of said top and having its opposite end portion formed with an aperture for engaging with said headed pin, whereby said top will be irremovably secured in place on the body when said strap is first engaged with said pin and the top is pressed down onto the body until the locking bar snaps into place in said recess.
